UNITED STATES PATENT OFFICE

EDMUND E. HANS, OF DETROIT, MICHIGAN

FUEL HEATER

Application filed October 20, 1922. Serial No. 595,773.

This invention relates to means for heating the fuel of internal combustion engines, whether in the liquid or vaporized state, by means of the lubricating oil which has been drawn from the crank case or other storage reservoir and heated by the exhaust gases of the engine for the purpose of driving off the gasoline which has become mixed with such oil by reason of leakage of the engine pistons which permitted the gasoline to pass to the crank case, and this invention consists in the combination of a receptacle for the oil and means to heat the receptacle by the exhaust gases of the engine, a fuel receptacle or conduit, and means to bring the heated oil into contact therewith.

It further consists in means embodying a thermostat for controlling the flow of oil through the heating device therefor so that the oil passing to the fuel heater will be of the desired temperature.

It also consists in means for controlling the action of the burnt gases upon the receptacle in which the oil is heated.

It also consists in the details of construction illustrated in the accompanying drawings and particularly pointed out in the claims.

In the accompanying drawings, Fig. 1 is a vertical section of special exhaust and intake manifolds to carry out my present invention. Fig. 2 is a similar section of another embodiment of the invention. Figs. 3 and 4 are sections on the lines 3—3 and 4—4 of Fig. 2 respectively. Fig. 5 is an elevation of a modified form of control device for the exhaust gases. Fig. 6 is a detail of the construction shown in Fig. 5. Fig. 7 is an elevation of another control device for the exhaust gases. Fig. 8 is a vertical section of another form of oil heating device. Fig. 9 is a vertical section of another form of oil heater. Fig. 10 is a section on the line 10—10 of Fig. 9. Fig. 11 is a vertical section of another form of oil heater. Fig. 12 is a section on the line 12—12 of Fig. 11. Fig. 13 is a vertical section of another form of fuel heater. Fig. 14 is a section on the line 14—14 of Fig. 13.

Similar reference characters refer to like parts throughout the several views.

Heating of fuel of internal combustion en-

gines by means of the cooling water of the engine and by means of the exhaust gases directly has been carried out to some extent. Heating of the lubricating oil of internal combustion engines in order to drive off the gasoline or other fuel which may have become mixed therewith has also been suggested and means have been suggested for cooling this lubricating oil after it has been brought to a high temperature to evaporate the volatile impurities. Several devices for carrying out this idea are shown in my pending application Serial Number 537,128, filed February 16, 1922.

The present invention embodies mechanism whereby the heat taken up by the lubricating oil while being purified to remove the volatile gasoline, kerosene, alcohol, water or other impurities, is utilized to heat the fuel passing to the engine. The temperature of the fuel can be much more easily controlled when using this heated lubricating oil than when the circulating water or the exhaust gases are made use of.

In Fig. 2 of the drawings an exhaust manifold 1 having ports 2 and a fuel or intake manifold 3 having ports 4 are shown independent of the engine, but as the construction of the engine forms no part of the present invention, and as this present invention is adapted to be used in connection with every type of internal combustion engine, no attempt is made to show the manner of connecting the manifolds to the engine or the construction of the engine.

The exhaust manifold 1 is connected to a passage 5 in which are mounted the valves 6 and 7 which control the openings 8 and 9 respectively. Adjacent the passage 5 is an oil-heating chamber 10 on the upper end of which is mounted a valve chamber 12. The lubricating oil passes to this oil-heating chamber through a pipe 11 and any desired means may be employed to cause it to flow from this oil-heating chamber to the fuel heater.

Extending down from the valve chamber 12 and into the oil-heating chamber 10 is a substantially cylindrical and preferably corrugated container 13, wherein the oil is heated

100

by means of the exhaust which passes into this chamber 10 through the opening 8 and escapes therefrom through the opening 9 when the valves 6 and 7 are in the position shown in Fig. 2. The pipe 14 extends up from nearly the bottom of this container 13 and connects at its upper end to a passage 15 in a wall of the valve chamber, and a pipe 16 extends from this passage to the separating chamber 17. The result will be that the oil will stand in the valve chamber 12 at about the height of the intake end 18 of the pipe 16. Instead of using a pipe 16, a passage 19 may be cored in the wall of this valve chamber 12, as indicated in Fig. 3.

15 Mounted in the valve chamber is a seat 20 for the valve 21 which is normally held on its seat by means of the spring 22. So long as the oil in the valve chamber remains below the maximum temperature, the thermostat 23 will not engage with the stem 24 of the valve 21 to lift it from its seat and only a minimum amount of oil will enter the valve chamber through the pipe 11 and the small passage 25, but as soon as the temperature of the oil around the thermostat 23 has reached the desired point, the thermostat will lift the valve 21 and an additional amount of oil will flow down into the valve chamber and into the container 13.

20 The oil from the pipe 16 or passage 19, depending upon which is used, flows into a separating chamber 17 which is formed with a series of transverse partitions 26, alternate partitions being formed with openings 27 at opposite ends so that this heated oil when trickling through these holes 27 and flowing across the partitions 26 will freely give up the volatile impurities which flow back upward through the pipe 16 to its intake end 18 and then through the passage 28 back into the valve chamber, from which they may escape through the opening 29.

25 A pipe 31 is shown connecting to this separating chamber 17 and to the intake manifold 3 of the engine and may be provided with a valve 32. If the hole 29 is plugged or omitted and the valve 32 opened, these volatile impurities will be conducted to the intake manifold 3 so that they may pass into the engine as part of the fuel therefor. The valve 7 may be omitted if desired.

30 The heated oil passes from the separating chamber 17 to the fuel-heating chamber 34 by means of a pipe 35. This chamber 34 may be of any desired construction and several types will be explained later on. In Fig. 2, however, it is shown to have a partition 35' dividing it into two parts, one being a passage 36 which connects with the main portion 34 through an opening 37 and through a much smaller opening 38 at the lower end of this partition 35'. A pipe 39 conducts 35 the oil from the passage 36 back to the main

oil receptacle which may be the crank case of the engine, if desired.

Upon the stopping, during cold weather, of the engine to which this mechanism is attached, any oil remaining in the chamber 34 congeals and it would become extremely difficult to force oil through the pipe 35 into this chamber to warm and then expel the oil therein, but where the small passage 38 is left in the partition 35', the oil in this chamber 34 will drain out after the flow through the pipe 35 has stopped.

20 While the valves 6 and 7, or the valve 6 alone if the valve 7 is omitted, may be operated by hand, the mechanism shown in Fig. 2 may be employed. Attached to the wall of the separating chamber 17 by means of a post 42 is a thermostat 43 mounted in a closed chamber 44 of any desired construction, and a small shaft 45 is mounted in the walls of this chamber and has a lever arm 47 attached to it within the chamber in the path of the free end of the thermostat 43. Outside the chamber and attached to the shaft 45 is another lever arm 46 which connects to a link 48 that attaches to a small lever arm 49 attached to the pivot shaft 50 of the valve 6. If the valve 7 is used, a lever arm 52 attached to it connects to a lever arm 53 attached to the valve 6 by means of a link 54 so that these two valves will open and close simultaneously.

25 When the temperature within the chamber 44 reaches a predetermined height because of the temperature of the oil passing through the separating chamber 17, these valves 6 and 7 will be slowly closed and thus control the temperature within this purifying chamber 17. By means of these two thermostats 23 and 43, therefore, the temperature of the oil passing through the pipe 35 can be absolutely controlled.

30 In the structure shown in Fig. 1, the exhaust manifold 61 has mounted on it or formed as part thereof a by-pass 62 into which an oil-heating chamber 63 extends. The lubricating oil passes into this chamber through a pipe 64 controlled by a valve 65, if desired, and passes from this chamber into a passage 66 from which it flows through a pipe 67. The intake manifold 68 is surrounded by a jacket 69 into the lower end of which the pipe 67 connects, while a pipe 70 connects into the top of this jacket and may extend to any storage receptacle, the crank case of the engine being preferred. A pipe 72 is shown to extend across through the intake manifold and connect into this jacket at its ends in order to permit the oil to pass freely from one side to the other of this jacket under the difference in pressure which usually occurs, and the pipe being in the path of the fuel as it passes from the carburetor 73 to the ports 74, a maximum heating effect of this portion of the oil will be secured.

The throttle 76 of this carburetor is indicated in dotted lines on a shaft 77 and to this shaft are shown connected the two lever arms 78 and 79, the former connecting by means of a link 80 to a lever arm 81 on the shaft 82 which carries the valve 83, and the latter connecting to the throttle control rod 84. The operator of the engine when opening the throttle 76 swings the valve 83 up toward the opening 85 so as to reduce the proportion of exhaust gases which pass around the oil-heating chamber 63. It will be noticed that in this case, all of the exhaust passes around the oil-heating chamber when the oil is cold, which is when the engine begins to run, and that as the engine warms up, a smaller proportion of the exhaust is employed to heat the oil. When the engine is running at high speed its exhaust gases are extremely hot and it is therefore advisable to reduce the proportions which contact with the oil-heating chamber. If any volatile impurities occur in the lubricating oil and these are volatilized in the oil-heating chamber 63, they may be carried off through a pipe 86. In order to prevent the jacket 69 being filled with congealed oil, a drain pipe 87 may be attached opposite the discharge end of the pipe 67 so as to permit the slow drainage of this chamber 69.

The details of construction and the proportions of the parts of this oil and fuel heating mechanism may all be changed without departing from the spirit of my invention as set forth in the following claims. Several examples of these changes and modifications are shown in Figs. 5 to 14 of the drawings.

In Fig. 5 a combined manually and automatically operated exhaust control valve mechanism is shown. The exhaust passage 5 has attached to it a plate 88 in which is mounted the shaft 89 which carries the exhaust valve 90 which may be similar to the valve 6 shown in Fig. 2. To this shaft is attached a bar 91 which constitutes two lever arms, and this shaft is normally held in the position shown in Fig. 5, which is with the exhaust valve horizontal, by means of a spring 92. Attached to the upper end of this bar 91 is a link 94 which connects to the horizontally movable rod 95 slidable in a guide 96, while a second rod 97, similarly slidable in this guide, connects to the lower end of the bar 91 by means of a link 98. A horizontally slidable bar 100 is provided with a slot 101 to receive pins 102 carried at the lower end of the bifurcated rod 103 and this rod is connected to a thermostat 104 mounted in a chamber 105 which has inlet and outlet pipes 106. These pipes may carry the circulating water of the engine or the heated lubricating oil to this thermostat and thereby determine whether the rod 100 shall be raised sufficiently high to engage the end of the rod 95 or the end of the rod 97.

The slotted rod 101 is preferably provided with a pin 107 which is slidable in the slot 108 formed in the guide rod 109 which connects to the operating mechanism of the throttle of the engine. When the engine is idling or when the engine is cold, the throttle of the engine is in what is termed the closed position, that is, in the position which is as nearly closed as possible and still permit sufficient fuel to pass to the engine to keep it running. Under these conditions the valve 90 is across the exhaust passage, that is, in the position of the valve 6 in Fig. 2. The result is that substantially all of the exhaust gases pass into the oil-heating chamber and that the oil becomes quite hot. When this oil then passes through the small chamber 105 by means of the pipes 106, the thermostat 104 will be affected thereby and will lift the actuating rod 100 until it is in alinement with the rod 95. If now the operator opens the throttle and thereby slides the rod 100 to the left in Fig. 5, he will cause the valve 90 to swing toward vertical position and thus reduce the proportion of the exhaust gases which flow to the oil heating chamber. If the oil passing to the chamber 105 is not sufficiently hot to thus affect the thermostat 104, the longitudinal movements of the rod 100 will have no effect on the valve 90, which remains in horizontal position until the rod 100 is elevated.

When the rod 95 is pushed in the full distance so that the lower end of the bar 91 passes below the shaft 89, the spring 92 will throw this valve 90 to vertical position and hold it there until the temperature of the liquid circulating through the chamber 105 falls sufficiently to permit the rod 100 to aline with the rod 97. If now the throttle actuating mechanism is so moved as to carry the rod 100 to the left, it will engage the right hand end of the rod 97 and swing the parts back to the position indicated by the solid lines in Fig. 5. It will therefore be seen that the thermostat 104 controls the position of the valve in the exhaust passage but that this valve is actuated by the operator of the vehicle through the throttle-operating mechanism. It will also be understood that instead of the chamber 105 receiving the lubricating oil from the oil-heating chamber, that these pipes 106 can convey a part of the cooling water of the engine or may even carry a part of the exhaust. In each case the operation will be determined by the temperature of the engine itself.

In Fig. 2 the receptacle 13 for the oil is shown to be cylindrical and corrugated. In Figs. 9 and 10 the container 110 is shown rectangular and is placed directly opposite one or more of the exhaust ports 111 of the engine and within the exhaust passage 112. Figs. 9 and 10 indicate how the exhaust will normally strike against the pivoted shields 113, but the dotted lines in Fig. 9 indicate how these shields may be swung to horizontal position

to permit the exhaust to impinge directly on the oil container 110. Any desired means may be employed to turn the shafts 114 on which these shields are mounted, a handle 115 being shown in Fig. 10. These shields are 5 preferably provided with wings 116 to prevent the hot gases from passing around the shields and impinging on the ends and on the back of this container 110.

10 In the internal combustion engines employed in motor vehicles the exhaust gases are often found to be incandescent, that is, the combustion seems to be continued into the exhaust passage so that when the exhaust manifold is removed tongues of flame shoot out through the exhaust ports. In the construction shown in the drawings the actual flame is provided for to heat the oil containers and for this reason the shields 113 are 15 provided with these wings 116. The construction shown in Fig. 2 is admirably adapted for high speed engines, but where the engines operate at comparatively low speeds, the oil container should be moved up into close proximity to the exhaust ports of the engine so that a maximum effect of the heat of the exhaust may be obtained.

19 Figs. 11 and 12 disclose a construction which is adapted to be used for heating the oil or for heating the fuel. Where this construction is used as a fuel heater, the shells 118 and 119 are connected by the heads 120 and 121 and by the circular partitions 122 which are provided with openings 123 to permit the oil to slowly pass through this container. The oil enters through the passage 124 and leaves through the passage 125 and the volatile impurities may be drawn off through the pipe 126a. In this case the central cylinder 119 constitutes a part of the fuel 20 passage of the engine. Where this construction is employed as an oil heater, the head 120 may be attached to the flange 126 shown in Fig. 1 and the exhaust will pass down through the central passage 119.

25 In Figs. 13 and 14 a structure is shown which may also be employed as either the fuel-heating chamber or the oil-heating chamber. When employed as the fuel-heating chamber, the shell 130 will constitute the fuel passage which is interrupted at intervals by means of the transverse walls or fins 131, 132 and 133. The position and the arrangement of these walls may be varied within very 30 wide limits. Extending from the shell 130 into the space between them and the outer shell 134 are the short fins 135 which take up the heat of the oil which enters at 136 and passes around the shell 130 to the passage 137. This heat is communicated to the inner fins 131, 132 and 133. Any volatile matter 35 in the oil may pass out through the small pipe 138. As explained in connection with the other fuel heaters, a small relief pipe 139 will be connected into the space between the shells

130 and 134 to drain the space between these two shells when the engine is stopped. When this construction is used as an oil heater, the exhaust will pass through the shell 130 and thus heat will be communicated to the fins 70 131, 132 and 133 to the shell 130 and by the small ribs 135 to the oil between the shells 130 and 134. In this case the small passage 139 may be omitted.

75 In the construction shown in Fig. 7, the exhaust passage 140 is adjacent the oil-heating chamber 141 and a valve 142 to control the passage of the exhaust into the oil-heating chamber is mounted on the shaft 143 to which an operating arm 144 is attached. A cylinder 145 contains a piston 146 whose rod 147 connects to the operating arm 144 by means of the link 148. The intake manifold 149 connects to a valve chamber 150 by means of a pipe 152 and this valve chamber connects to one end of the cylinder 145 by means of a pipe 153. A thermostat chamber 154 connects to the oil-container in the heating chamber for the oil by means of a pipe 155 and the oil escapes from this chamber 154 through the pipe 156 and normally will flow back to the 80 crank case.

85 The thermostat 157 connects to the valve 158 by means of the rod 159. When the oil has reached a predetermined temperature, the free arm of the thermostat 157 moves up as shown in Fig. 7 and lifts the valve 158 from its seat across the lower end of the pipe 152 and when so lifted this valve permits a connection between the pipes 152 and 153 and the suction of the intake manifold to draw the piston 146 to the position shown in this figure and to swing the valve 142 to vertical position. As soon, however, as the temperature of the oil falls below a predetermined point, the valve 158 closes the lower end of the pipe 152 and breaks the connection between it and the pipe 153 which results in the suction within the cylinder being broken and permits the spring 160 to swing the lever 100 arm 144 to carry the valve 142 to horizontal position, which again forces the exhaust to pass through the oil-heating chamber and thereby raise the temperature of the oil passing through this thermostat chamber 154. In this case again the temperature of the oil 105 controls the action of the exhaust gases on the container within the oil-heating chamber. It will be understood that the manifold 149 is merely used as an example of mechanism for creating the vacuum and that a small bleed hole may be provided in the piston 146 or at the end of cylinder 145 adjacent pipe 153 to reduce the vacuum therein when valve 158 is closed or other well-known means provided 110 for the purpose.

115 In the construction shown in Fig. 8 the exhaust enters the exhaust passage 163 through ports 164 and passes down through the continuation 165 of this passage, and the burn- 120 125

ing gas impinges on the oil container 166. A pair of shafts 167 are mounted at the upper level of this passage 163 and to these shafts are connected the valves 168. Lever arms 169 and 170 are connected to these shafts 167 and a link 171 connects these lever arms. A third lever arm 172 is attached to one of these shafts and to an operating rod 173 which may have an operating knob 174 attached to its opposite end. When this knob is in the position shown in the drawing and the two valves are in the upright position as shown in solid lines, the exhaust can sweep up along the entire length of the container 166 and a large amount of heat is imparted thereto, but when less heat is required, the knob 174 is pushed in and the valves are swung down to dotted line position, which virtually reduces the capacity of the oil container for absorbing heat one half.

20 Mounted on this heating chamber is a control chamber 175 in which a valve seat 176 for the valve 177 is mounted. The stem 178 of this valve is slideable by means of the thermostat 179 against the pressure of the spring 180. The oil enters through the passage 181 and passes down into the chamber 175 and into the oil container 166, then up through the pipe 184 and out through the pipe 185.

Resting on the lower arm of the thermostat 179 is a rod 186 which is connected by an electric wire 188 to a current source. When the temperature of the oil in the chamber 175 has reached the predetermined maximum, this rod 186 will engage the contact 189 on the wire 190 and cause the lamp 191 to burn. The operator will then push in the handle 174 and reduce the effect of the exhaust. After the temperature of the oil drops below a predetermined point, the contact 192 on this rod 186 will engage the contact 193 at the end of the wire 194 and cause the lamp 195 to burn. These lamps are mounted on any desired support 196 through which they may be grounded in the usual manner. The 40 contacts are preferably within an enclosed chamber where the oil is not liable to reach them. The volatile vapors from the oil may pass off through a pipe 198. This signal mechanism may be used in any one of the 45 structures already described which is provided with a thermostat.

It will be understood that the structures shown in Figs. 11 to 14 inclusive may be connected to the air-intake openings of carbureters for the purpose of utilizing the heat of the purified oil to heat the air used in carbureting the liquid fuel.

I claim:—

1. In a fuel heater, the combination of the 60 exhaust passage of an internal combustion engine, a heating chamber for the lubricating oil of the engine adjacent the exhaust passage, a pipe to conduct the oil to the heating chamber, means to supply fuel to the engine provided with a container for heated

oil, a conduit for conveying heated oil from the heating chamber to said container and means dependent upon the temperature of oil in the heating chamber for maintaining the temperature thereof substantially uniform, whereby the oil conveyed to said container is of substantially uniform temperature.

2. In a fuel heater, the combination of the 70 exhaust passage of an internal combustion engine, a heating chamber for the lubricating oil of the engine adjacent the exhaust passage, a pipe to conduct the oil to the heating chamber, means to supply fuel to the engine provided with a container for heated oil, a conduit for conveying heated oil from the heating chamber to said container, and means dependent upon the temperature of the oil to control the flow of oil to the heating chamber.

3. In a fuel heater, the combination of the 75 exhaust passage of an internal combustion engine, a heating chamber for the lubricating oil of the engine adjacent the exhaust passage, a pipe to conduct the oil to the heating chamber, means to supply fuel to the engine provided with a container for heated oil, a conduit for conveying heated oil from the heating chamber to said container, and a thermostat to control the action of the exhaust on said heating chamber whereby the oil conveyed to said container is of substantially uniform temperature.

4. In an internal combustion engine, the 80 combination of an oil container in the path of the exhaust gases, means to by-pass the exhaust gases around said container, means to convey oil to said container, means to supply fuel to the engine embodying means to heat the fuel, a conduit to convey heated oil to said fuel heating means, and a thermostat to control the heating action of the exhaust gases whereby the oil conveyed to said container is of substantially uniform temperature.

5. In an internal combustion engine, the 85 combination of an oil container adjacent the exhaust passage, temperature controlled means to by-pass the exhaust gases around said heating container whereby the temperature of oil therein is maintained substantially uniform, means to convey oil to said container, means to supply fuel to the engine comprising means constructed to heat the fuel, and a conduit to convey heated oil to said fuel heating means.

6. In an internal combustion engine, the 90 combination of a heating chamber adjacent to the exhaust passage, means to by-pass the exhaust gases around said heating chamber, means to convey oil to and from said heating chamber, and thermostatic means to control the flow of oil and the operation of said by-pass means.

7. In the lubricating system of an internal 95

- combustion engine an oil heating chamber and temperature controlled means for regulating the flow of oil thereto and the application of heat thereto.
- 5 8. In the lubricating system of an internal combustion engine an oil heating chamber, means affected by the temperature of oil in such chamber for controlling the flow of oil thereto and means affected by the temperature of the oil in such chamber for controlling the application of heat thereto.
- 10 9. In the lubricating system of an internal combustion engine an oil heating chamber, temperature controlled means for controlling the application of heat thereto and a thermostat submerged in the oil in said chamber for controlling the flow of oil thereto.
- 15 10. In the lubricating system of an internal combustion engine a heat exchange device including a chamber for the lubricating oil, an oil inlet to said chamber, an oil outlet from a high point in said chamber whereby the chamber is normally kept substantially full of oil and a bleed valve at a low point in the chamber permitting slow exit of oil therefrom.
- 20 11. In the lubricating system of an internal combustion engine a heat exchange device including a chamber for the lubricating oil, an oil inlet to said chamber, an oil outlet from a high point in said chamber, a bleed valve at a low point in said chamber permitting slow drainage of oil therefrom, and a vent for the escape of vapors produced in said chamber.
- 25 12. In an internal combustion engine the combination of an exhaust passage, a heating chamber extending into said passage, a pipe to supply the lubricating oil of the engine to said heating chamber, means to supply fuel to the engine provided with a container for heated oil, a conduit for conveying heated oil from the heating chamber to said container and means responsive to the temperature of the oil in said heating chamber to control the flow of oil thereto.
- 30 13. In an internal combustion engine the combination of an exhaust passage, a heating chamber extending into said passage, a pipe to supply the lubricating oil of the engine to said heating chamber, means to supply fuel to the engine provided with a container for heated oil, a conduit for conveying heated oil from the heating chamber to said container and a thermostat in said heating chamber for controlling the flow of oil thereto.
- 35 14. In an internal combustion engine the combination of an exhaust passage, a heating chamber extending into said passage, a conduit for supplying the lubricating oil of the engine to said heating chamber, means to supply fuel to the engine provided with a container for heated oil, means comprising conduits and a separating chamber for con-
- ducting heated oil from said heating chamber to said container, means responsive to the temperature of the oil in said heating chamber to control the flow of oil thereto and a vent for vapors from said separating chamber.
- 40 15. In an internal combustion engine the combination of an exhaust passage, a heating chamber extending into said passage, a conduit for supplying the lubricating oil of the engine to said heating chamber, means to supply fuel to the engine provided with a container for heated oil, means comprising conduits and a separating chamber for conducting heated oil from said heating chamber to said container, means responsive to the temperature of the oil in said heating chamber to control the flow of oil thereto and means for conducting vapors from said separating chamber to the intake of said engine.
